Primary Examiner — John Windmuller*Assistant Examiner* — Steven Czyz(74) *Attorney, Agent, or Firm* — Knobbe Martens Olson & Bear LLP**CLAIM**

The ornamental design for a bow, as shown and described.

DESCRIPTION

FIG. 1 is a front elevational view of a first of a bow showing my new design.

FIG. 2 is a front perspective thereof.

FIG. 3 is a rear perspective thereof.

FIG. 4 is a top plan view thereof.

FIG. 5 is a bottom plan view thereof.

FIG. 6 is a right side elevational view thereof.

FIG. 7 is a left side elevational view thereof.

FIG. 8 is a front elevational view of one of the crystals attached to the bow shown separately for ease of disclosure.

FIG. 9 is a front perspective view thereof shown separately for ease of disclosure; and,

FIG. 10 is a side view thereof shown separately for ease of disclosure.

The broken lines depict portions of the article that form no part of the claimed design. The crystals shown in FIGS. 8-10 are shiny and transparent.
